UNITED STATES PATENT OFFICE.

ARTHUR LABELLE, OF MONTREAL, CANADA.

SNOW-PLOW.

SPECIFICATION forming part of Letters Patent No. 768,607, dated August 30, 1904.

Application filed April 4, 1904. Serial No. 201,607. (No model.)

To all whom it may concern:

Be it known that I, ARTHUR LABELLE, a subject of the King of Great Britain, residing in the city and district of Montreal, in the Province of Quebec, Canada, have invented certain new and useful Improvements in Snow-Plows; and I do hereby declare that the following is a full, clear, and exact description of the invention, such as will enable others skilled in the art to which it appertains to make and use the same.

This invention relates to new and useful improvements in snow-plows adapted for use upon railroads for the purpose of clearing snow from the tracks thereof; and it consists in certain features of novelty in the construction and operation of the parts thereof, all as hereinafter more fully described, and specifically set forth in the claims.

The object of the invention is to produce a snow-plow of the character described which will be so constructed as to cut its way through an embankment of snow and present only such portion of the snow to the wedge constituting the plow proper as will be necessary for clearing a given track, thus avoiding the packing of snow, which has been found to be an obstacle in the way of the successful operation of snow-plows heretofore suggested.

Referring to the drawings, in which similar numerals of reference indicate corresponding parts in all the views, Figure 1 is a side elevational view, partly broken away for the purpose of better showing details of construction. Fig. 2 is a plan view of the snow-plow with the roof of the cabin thereof removed. Fig. 3 is a vertical sectional view of the operative mechanism disclosed in the plan view Fig. 4, taken on line 3 3 of said Fig. 4, while Fig. 4 is a plan view, taken in section through the cabin, illustrating the means for manipulating the plow.

Referring to the drawings, 1 is a rear truck provided with supporting-wheels 2 and a transverse bolster 3, adapted to support the platform 4, upon which platform is mounted the plow, which for convenience is hereinafter referred to as a "wedge." At the forward end of the platform 4 are supporting-wheels 5, which are of less diameter than the wheels

2, whereby the forward end of the platform inclines from the point marked X to the extreme forward end thereof, which is supported only a few inches above the surface of the track-rails 6.

55

Mounted upon the platform 4 is a housing or cabin 7, adapted to be used by the operators of the plow for the purpose of sheltering such operators from flying material operated upon in the process of cutting through the snow.

Extending longitudinally of the car comprising the truck 1, bolster 3, platform 4, and supporting means 5 is a sheathing 8, which extends from the truck-platform down to a point just slightly removed from the said track-rails 6, so as to prevent the passage of snow laterally under the truck, which snow might have a tendency to dislodge the car from the track. Projecting slightly beyond the forward end 9 of the car and extending thence upwardly of the inclined floor 10 are side walls 11, which are provided with vertical braces 12, transverse braces 13, and with the doors 14, connected to the side walls by means of the strap-hinges 15, as shown in the drawings, or by any other convenient securing means. Projecting laterally from the walls 11, as best shown in Fig. 2, are socketed members 16, which are adapted to receive vertically-reciprocatory rods or bolts connected with the doors 14 for the purpose of securing the doors in a forward position, as shown by the dotted lines in Fig. 2, this position being desirable when the point 17 of the plow is swung toward the left or lower side, as shown in the drawings. It will be noted that the door shown dotted in Fig. 2 is at the upper side or right-hand side as the apparatus advances; but when the plow is turned to that position it is preferred that the opposite door shall be open and the door at the right-hand side shall be closed.

Suitably supported upon the platform 4 is a wedge-shaped structure comprising the wings 18, which converge toward the point 17, as best shown in Fig. 2. The point 17 may comprise a casting, if desired, to which is secured the said wings 18, the said casting affording a better resisting medium for the

100

impact of the snow and ice which will be projected thereagainst in the practical use of the apparatus. Connected with the inclined floor 10 at each side of said floor are sockets 19, 5 into which sockets 19 pins passing through the lugs 20 on the point 17 may be projected for the purpose of securing the wedge in a position wherein the point will be held at either side of the said inclined floor 10. Between the wings 18, at the forward ends thereof and just behind the point 17, is a supporting-roller 21, upon which the said wedge will ride in its lateral movement. Extending transversely between the wings 18 within the lower 15 portion thereof are brace-rods 22, which by means of angular extensions 23 are connected with said wings and which extend from thence to the plate 24, (shown in Figs. 3 and 4,) while a second transverse brace 25, also 20 connected with said wings, extends to said plate 24, the braces 22 and 25 being connected with said plate at opposite sides of the central opening in said plate 24, upon which it turns. Below the plate 24 is a second plate 25 25, between which and said plate 24 friction-reducing balls 27 are provided, and the plate 24 is freely rotatable upon said plate 26 when desired. Connected with the upper portion of the said wings 18 are a plurality of brace-rods 28 and 28^a, which are connected to a yoke 30 29 or which terminate in a yoke embracing the upper end of the fixed standard 30.

Within the cabin 7 is provided an ordinary brake-staff 31, supported within the bracket 32 and by means of the base-plate 33 between the flooring 10^a and the superposed flooring 34 within said housing. Upon the said brake-staff 31 is a small pinion 35, which meshes with a gear 36 upon the shaft 37, suitably supported between the flooring 10^a and the superposed flooring 34, while on said shaft 37 is a sprocket 38, and engaging with said sprocket is a chain 39, which extends thence to the hangers 40, connected to the inner faces of 45 the said wings 18. An ordinary hand-wheel, as 41, on the brake-staff 31 is adapted for rotating said brake-staff, pinion 35, gear 36, and actuating the chain 39 through the sprocket 38, and thereby swinging the wedge upon the 50 pivot-plates 24 and 26. (Shown in Figs. 3 and 4.) The standard 31, as will be noted, is of an increased diameter at its lower portion and is fixed in position by means of the plate 42, which is connected with the flooring 10^a 55 by means of bolts 43 projected through the timbers thereof. As the wedge must necessarily rock to some extent in its movement from the central point 44 (shown in Fig. 2) to the extreme sides of the car, owing to the inclination of the flooring 10, it is necessary that the plates 24 and 26 be so formed as to compensate for such rocking, and for this reason the opening 45 in the plates 24 and 26 is larger at the top than at the bottom, and as the brace-rods 22 and 25 are connected at opposite sides

of the plate 24 at opposite sides of the pivotal opening 45 it is evident that more or less rocking of the members 24 and 26 will result from the shifting of the wedge. This is compensated for by means of the plate 46, the upper 70 face of which is curved approximately in an arc of a circle struck from the yoke 29 at the upper end of said standard 30, the said plate 46 being a part of the plate 42 or connected therewith in such manner as to be fixed against 75 movement thereon. Upon the advance face of the cabin 7 are provided a plurality of loops or eyes 48 at different distances from the sides thereof, and the hooks 49 are adapted to be connected with the lugs 50 upon the wings 18 80 and engage with said loops 48, or, if desired, a number of hooks may be connected with said loops adapted to engage with eyelets on the wings.

For the purpose of facilitating the lateral 85 shifting of the wedge and to assist in supporting the rear thereof friction-rollers 51 are provided, one upon each inner side of the wings 18, as best shown in Fig. 3, the said rollers assisting in supporting the structure of said 90 wedge.

The operation of my improved apparatus is as follows: An engine or other suitable means being connected with the structure hereinbefore described it is propelled over the tracks 95 6 and the advance end thereof forced into the snow, which is cut by means of the said walls 11, so that only such portion thereof as is necessary to permit the passage of trains will be disturbed, a single track being cleared only 100 at one time. In driving the apparatus forward snow will ride up the inclined floor 10, and if it is a single track the point 17 of the wedge may be supported centrally of the car; but if there is a track either at the right or 105 left of the track on which the apparatus is being propelled the wedge will be turned by means of the hand-wheel 41 and its appurtenant connections to such position that the snow will impinge only one face of said 110 wedge and be driven either to the right or left, as may be desired, thereby cutting, lifting up, and throwing to one side or to both sides of the track the snow which it is desired to remove without in any manner disturbing the surrounding bed of snow. As it 115 has been found in practice that the snow becomes densely packed and has been almost impossible to remove in some instances, the cutting and separation from the main bed of that portion which it is desired to remove is considered of great advantage, wherefore the cutting edges 52 of the side walls 11 are found to be of great utility, these cutting edges extending beyond the car a sufficient 120 distance for practical use.

While I have shown in the accompanying drawings the preferred form of my invention, it will be understood that I do not limit myself to the precise form shown, for many 125

of the details may be changed in form or position without affecting the operativeness or utility of my invention, and I therefore reserve the right to make all such modifications 5 as are included within the scope of the following claims or of mechanical equivalents to the structures set forth.

Having described my invention, what I claim, and desire to secure by Letters Patent, 10 is—

1. In a snow-plow, a truck, a platform, an inclined slide, side walls, and doors thereon in combination with a pivoted wedge, and means for swinging said wedge. 15
2. In a snow-plow, a truck-frame having an inclined floor, side walls therefor, a wedge, transverse braces within the wider part of said wedge, bearings connected with said braces, an approximately vertical shaft in 20 said bearings, and means for swinging said wedge on said shaft.
3. In a snow-plow, a car provided with an approximately level platform, an inclined forward portion, walls rising vertically from 25 said inclined portion, said walls having an advance cutting edge, doors pivotally connected with said walls, and a laterally-movable wedge supported near the upper end of said incline.
4. In a snow-plow, a car with an inclined 30 forward floor portion, side walls rising vertically therefrom, said walls having advance cutting edges, a laterally-movable wedge carried by said car, a standard upon which said wedge is moved, yokes extending from said 35 wedge about said standard near the upper and lower ends of said standard, and means connected with said wedge for moving the same upon its axis.

5. In a snow-plow, a car, with side walls having an advanced cutting edge, a laterally- 40 movable wedge upon said car, a pivotal support therefor, means for connecting the said wedge to said pivotal support, and means for moving the same upon its axis.

6. In a snow-plow, a car with an inclined 45 forward portion, walls at the sides thereof, doors in said walls, a wedge comprising a point-section, and diverging wings connected therewith, transverse braces near the upper and lower portions of said wings, a plate connected with said lower braces, a bearing-plate upon which said plate is supported, a standard projected through said plate and engaging the upper braces, and means for swinging said wedge upon said standard as a pivot. 50

7. In a snow-plow, a point-section, as 17, diverging wings connected therewith, top and bottom braces connected between said wings, a yoke connected with said top braces, a perforated plate connected with said bottom 60 braces, a standard projected through said plate and said yoke, and means for moving the said members upon said standard.

8. In a snow-plow, a car, locking-lugs connected with said car and snow-plow comprising a wedge supported thereon, said wedge including a point as 17 and diverging wings connected therewith, and laterally-projecting perforated lugs on said point adapted to be locked to the lugs on the car. 65

In witness whereof I have hereunto set my hand in the presence of two witnesses.

ARTHUR LABELLE.
